Application June 7, 1951, Serial No. 230,304

23 Claims. (Cl. 66—126)

1

This invention relates to a friction box drive in a full-fashioned knitting machine.

The ordinary full-fashioned knitting machine feeds yarn to be knit into fabric by means of one or more yarn carriers which are reciprocated parallel to integrally mounted banks of aligned needles. When in use, the main yarn carrier or carriers, laying yarn across the full width of the fabric, are driven by friction boxes having frictional engagement with a full speed friction box rod and the reinforcing carriers are driven by the same or other friction boxes having frictional engagement with a slow speed friction box rod. Each of the friction box rods has a greater traverse than the yarn carrier it drives, the path of the latter being limited by stops carried by nuts mounted on threaded spindles or worms which are rotated automatically as part of fashioning operations. Therefore, during the latter portion of each stroke of the friction box rods, the rods slide through the friction boxes while the boxes are stationary. It is essential that the boxes and particularly those driving the main yarn carriers start to move simultaneously with the full speed rod at each reversal of the movement of the rod in order to maintain the boxes in timed relation to other parts of the machine. Therefore, in order to prevent or reduce to a minimum slippage of the boxes on the full speed rod at the start of each movement of the boxes the frictional grip of the boxes on the rod must be quite strong with the result that the relative sliding movement between the boxes and rod when the boxes are stationary causes a high rate of wear and overheating of the parts. In fact, it is ordinary to cool the rods by circulating liquid therethrough.

In addition to the problem of quick starting of the friction boxes driving the main yarn carriers, there is the problem of stopping them. Unless special means is provided to slow the boxes before the yarn carrier rods strike their end stops, the resulting wear, the strain caused by the impact of the carrier rods on the end stops, and the noise of such impacts are highly objectionable. So called shock absorbers are therefore ordinarily placed on full-fashioned knitting machines. These have been quite successful in reducing the noise but the slippage of the boxes when starting their strokes, caused by the excessive wear between the boxes and the full speed friction box rod, has been sufficient to frequently throw the shock absorbers out of proper timing with consequent reduction or loss of their desired functions.

It is an object of the present invention to provide a means for reciprocating a friction box for

2

a yarn carrier which does not depend entirely on frictional engagement between two members for its effect.

Another object of the invention is to provide a means for reciprocating a friction box which is associated with a retarding or shock absorber means in such a way that the desired timing of the two functions is maintained.

With these and other objects in view which will become apparent from the following detailed description of the illustrative and practical embodiment of the invention shown in the accompanying drawings, the invention comprises the novel method steps, elements, features of construction and combination of parts in cooperative relationship, as hereinafter pointed out in the claims.

In the drawings:

Figure 1 is a sectional elevation of a full-fashioned knitting machine to which the invention has been applied the view being taken on a vertical plane transverse to the length of the machine, near its center and looking from the left of the machine;

Fig. 2 is a front elevation on a reduced scale compared to Fig. 1 of a portion of the machine near its center, parts being omitted for purposes of illustration;

Fig. 3 is a plan view of that part of the machine shown in Fig. 2 indicated by the arrows 3—3 on Fig. 2;

Fig. 4 is a front elevational view of the portion of the machine shown in Fig. 1 looking substantially in the direction of the arrows 4—4 on said figure;

Fig. 5 is an elevational view of the mechanism of Fig. 4, looking in the direction of the arrows 5—5 parts being omitted for purposes of clarity of illustration;

Fig. 6 is a sectional elevational view taken substantially on the line 6—6 of Fig. 4 looking in the direction of the arrows;

Fig. 7 is a sectional view taken substantially on the line 7—7 of Fig. 4 looking in the direction of the arrows, certain of the parts being shown in elevation;

Fig. 8 is an enlarged detail view of a portion of the mechanism shown at the upper left of Fig. 2 and enlarged relative to Fig. 2;

Fig. 9 is an end elevational view of the mechanism of Fig. 8, looking in the direction of the arrows 9—9 and enlarged relative to Fig. 8;

Fig. 10 is a detail view taken substantially on the line 10—10 of Fig. 9, looking in the direction of the arrows, certain of the parts being in elevation and others in section;

Fig. 11 is an elevation of parts shown in Fig. 10

looking in the direction of the arrows 11-11 in Fig. 9;

Fig. 12 is a plan view on a much enlarged scale of the portion of the apparatus shown at the upper left of Fig. 2;

Fig. 13 is a plan view on a much enlarged scale of the portion of the apparatus shown in Fig. 2 and lying substantially between the arrows 13-13 of Fig. 2;

Fig. 14 is a sectional detail view taken substantially on the line 14-14 of Fig. 11;

Fig. 15 is a sectional detail view taken substantially on the line 15-15 of Fig. 5, looking in the direction of the arrows;

Fig. 16 is a detail view similar to a portion of Fig. 3 showing one of the stops for a friction box;

Fig. 17 is a detail plan view of the friction box arrangement shown in Fig. 2 and the stops therefor and including the stop shown in Fig. 16;

Fig. 18 is an enlarged detail view of certain of the parts shown in Fig. 3, the parts being shown in different positions relative to Fig. 3;

Fig. 19 is a view similar to a portion of Fig. 18 but with the parts in different positions relative to Fig. 18; and

Figs. 20, 21, 22, 23 and 24 are diagrammatic views showing the relative positions assumed by the parts of the apparatus according to the present invention just before the start, during and just after the end of a driving movement of a yarn carrier rod.

In the drawings and description, only the means necessary to a complete understanding of the invention are specifically set forth; further information as to the construction and operation of other related, usual and well known knitting machine elements, etc., may be found in one or more of the following publications:

1. Pamphlet entitled—Full-Fashioned Knitting Machines—published and copyrighted by the Textile Machine Works, Reading, Pennsylvania, in 1920.

2. Four Catalogs entitled—The “Reading” Full-Fashioned Knitting Machine Parts Catalog—published and copyrighted by the Textile Machine Works, in 1929, 1935, 1940 and 1947, respectively.

3. Booklet entitled—The “Reading” High Production Full-Fashioned Knitting Machine—which, forming a supplement to the above noted 1940 Parts Catalog of the Textile Machine Works, is a publication of the Textile Machine Works, copyrighted by the latter in 1940.

4. Pamphlet entitled—Knitting Machine Lectures—published by the Wyomissing Polytechnic Institute, Wyomissing, Pennsylvania, in 1935.

A method of knitting a stocking within the invention includes reciprocating an operating friction box mounted on a friction box rod of a full-fashioned knitting machine by applying a sufficient accelerating force to the friction box at the beginning of each yarn laying stroke of the box, in addition to the force generated by friction between the rod and the box, to prevent substantial slippage between the box and the rod, continuing the application of force from said source to said box in the initial direction at least until the box has attained a speed at which the source ceases to accelerate the box, interrupting or reducing the application or flow of force from said source to the box before the box reaches the end of its stroke irrespective of the length of stroke of the box, retarding the box before it reaches the end of its stroke, repeating said steps for the reverse movement of the box, and con-

tinuing to repeat said steps throughout the knitting of a major portion of the stocking. Also, it is a feature of the present invention to mount the driving box on the friction box rod much more loosely than is now ordinarily done to reduce the friction with consequent reduction in the heating and wear on the box and rod. This is permissible because a source of accelerating force other than the friction box rod is available to start the box at the beginning of each of its strokes.

The apparatus shown in the drawings comprises portions of a full-fashioned knitting machine to which the features of my apparatus invention have been applied or in which said features have been incorporated. Said apparatus includes, in addition to the ordinary friction box and reciprocating friction box rod, a bar member connected to the friction box rod or coulier cam to reciprocate with the box and a head mounted on said member together with an automatic clutch means connecting said head to said member at the start of each stroke of the rod, the connection being firm enough to prevent substantial slippage of the head on the member. Also, means, preferably cam controlled, are provided to act on the clutch means to release the head from its driving member. Preferably this clutch releasing means is combined with a means acting as a shock absorber to slow the head and box. In this case, two cam controlled blocks are used, one on each side of the head. A connection between the head and the friction box having no more than a slight lost motion serves to accelerate the box at the beginning of a stroke and to slow it down toward the end of a stroke to prevent shock. Preferably, a second friction box is provided fixed to said connection so as to avoid or prevent lost motion therebetween to ensure that no chatter will occur due to repeated disconnection and reconnection of said automatic clutch in the interval between the initial disconnection of such clutch and the final stopping of the friction box at the end of a stroke. Owing to the acceleration of the box through said connection, it is permissible to mount the box much looser on its rod than is ordinarily done. Preferably, in addition to the ordinary end stops for the yarn carrier rods and which also act to limit the stroke of the friction box, end stops for the friction box are provided which are movable together with the end stops for the yarn carrier rods. The cam for controlling the releasing means for the head clutch and for slowing the head preferably is reciprocatory and, in this case, moves at about one-half the speed of the slur cam and the high speed friction box rod.

Referring to Fig. 1 of the drawings, a main cam shaft is shown at 23. The knitting needles 26, together with their cooperating knitting elements such as sinkers 28, dividers 29 and jacks 30, are all operated from the cam shaft 23 by means which may be of known types, and are supported in a framework of which transverse center frame 31, front beam 32, back beam 34, center bed 35 and front bed or table 36 are usual features. Yarn to be knit by the needles is fed by yarn carriers, one of which is shown at 40. Each yarn carrier is fixed to a yarn carrier rod 42, nine of which are shown. Friction boxes are provided for driving rods 42 one of such boxes being shown at 44 in Figs. 2 and 17. Each friction box 44 has a slide 46 best shown in Figs. 1 and 17 and fixed to which is a handle 47 by which the slide 46 may be moved to engage a dog

49 on a desired one of rods 42 to reciprocate the rod between end stops 48, diagrammatically shown in Figs. 20 to 24. End stops 48 are mounted on nuts 50, which are carried in turn by threaded spindles 52 forming parts of automatic fashioning means by which the spindles 52 are turned at each fashioning operation to move the end stops 48, thereby varying the length of stroke of the yarn carrier and the width of the fabric. The means for turning spindles 52 is not shown but may be of an ordinary type.

The friction box 44 for driving the yarn carriers 40 is shown mounted on two reciprocating rods, a high speed rod 55 and a low or slow speed rod 56. Box 44 has two handles 57 and 58 whereby it may be frictionally engaged with either of the rods 55 and 56 as desired. Power for reciprocating rods 55, 56 is taken from the main cam shaft 25 by a jack shaft 60 shown in Fig. 2. A coulier cam 62 on shaft 60 reciprocates a floating link 64 in opposite directions, as viewed in Fig. 2. At one end, link 64 is pivoted to a lever 66 which is mounted for oscillatory movement on shaft 68 carried on the back beam 34. At its other end, link 64 is pivoted to an oscillatory lever 70 having a fixed pivot 72 at its upper end. Lever 66 operates the high speed rod 55 through a link 74 pivotally connected to both the upper end of lever 66 and a head 76 fixed to rod 55.

The low speed rod 56 is operated from lever 70 through a linkage beginning at a pivot pin 78 on lever 70 and a link 80 only one end of which is shown. This is for the reason that the functions performed by the low speed rod in part have no connection with the present invention and in part have been taken over by novel mechanism according to the present invention and which will be hereinafter described.

In order to facilitate movement of the friction box 44 with the rod 55 and to prevent relative movement between the box and rod at the beginning of a stroke of the rod, driving means additional to the rod 55 is shown, such means including clamps 82 on rod 55, the clamps being fastened by bolts or otherwise to a driving member or bar 84 (Figs. 2, 8, 9 and 12) which is thereby constrained to reciprocate at the same speed as the head 76. Mounted on bar 84 for movement with the bar and for movement relative thereto is a driving member or head 86 having releasable clutch means 88 (see Figs. 10 and 11) associated therewith for alternately clutching and unclutching the driving member 86 to and from the bar 84. Said clutch means comprises a block 90 which is shown in Figs. 10 and 14 as inserted in a recess in the head 86 and bolted therein in contact with one face of bar 84. Block 90 has recesses 92 and 93 therein with open sides against the bar 84. Recesses 92 and 93 are alike except that each is reversed relative to the other. The walls of recesses 92 and 93 opposite the bar 84, (see Fig. 10), are inclined away from the bar, the inclination, in the case of each recess, being toward the center of head 86. In each recess is one of a pair of roller type clutch elements 94. It will be seen that gravity tends to cause rollers 94 to move away from the surface of bar 84 but that this tendency is opposed by a pair of spring pressed plungers 95 which tend to keep the rollers normally in contact with both the surface of bar 84 and the bottoms of recesses 92 and 93. Consequently whenever bar 84 begins to move in either of the directions indicated by the arrows A or B in Fig. 10, the contact between the bar

and one roller 94 moves the roller to wedge it tightly between the bar and the block 90, thereby clutching head 86 firmly but releasably to the bar, whereby the head is adapted to accelerate one or a number of boxes operating yarn carrier rods. The same movement of bar 84 which causes one roller 94 to clutch the head 86 to the bar moves the other roller clear of clutching engagement. Block 90 also has two plungers or tappet pieces 96, between the ends of the block and the rollers for moving roller clutch members 94 when it is desired to release the head 86 from bar 84. Means for operating the tappet pieces 96 also forms, in the mechanism shown herein, a part of a means for retarding the movement of head 86 when unclutched and will be described below.

Means for transmitting an accelerating force from head 86 to a friction box 44 is shown as comprising a rod 98, and a driving connection between the head 86 and rod 98. The driving connection, as best shown in Figs. 9, 10, 11 and 14, includes a pair of collars 100 on the rod and a tongue 102 mounted on head 86 in a way to maintain the tongue in substantially fixed relation to the head, and extending between said collars to transmit movement from the head to the rod in either direction depending on the direction of motion of the bar 84 and the head. Tongue 102 is shown as forming the lower end of a member 104 pivotally carried on a stud 106 secured in the head 86. The member 104 is maintained in the position of Fig. 11 by a pin 107, one end of which is fixed in an extension 108 of the member 104 and the other end fixed in the driving head 86, as shown in Fig. 14. An over-the-center spring 110 is connected between an extension 112 of the member 104 and the driving head 86. The pin 107 not only acts to hold the member 104 in the position of Fig. 11 as hereinbefore set forth but also acts as a safety between the driving head 86 and the rod 98, the pin being an intentional weak spot easily sheared in case movement of either the head or rod becomes obstructed in relation to the other. Upon shearing of the pin 107 the member 104 will be rotated either clockwise or counterclockwise about the stud 106, depending upon the direction of travel of the driving head 86, thereby removing the tongue 102 from its position between the collars 100. Upon movement of the member 104 either clockwise or counterclockwise about the stud 106, the spring 110 will draw either the extension 108 of the lower tongue portion 102 against a stop pin 114 and maintain the tongue out of the path of the collars 100 until the machine is brought to a stop and the difficulty causing the pin shearing action is corrected.

The driving connection between rod 98 and box 44 is best shown in Fig. 17 and includes a pair of blocks 116 fixed to the rod and a tongue 118 movably connected to the box 44 but lying, when the box is in use, between the blocks 116 to receive driving impulses therefrom. As shown in Figs. 17 and 20, slight clearances 120 are provided between the blocks 116 and the tongue 118 for purposes hereinafter set forth. The tongue 118 is hinged or otherwise movably connected to the friction box 44 so that the box can be disconnected from the rod 98 when it is desired to move it out of the knitting field to take it out of action. The tongue 118 must also be disconnected from the rod 98 when the box 44 is connected to the slow speed friction box rod 56.

While the yarn carrier rods such as 42, Fig. 1, and the carrier rod end stops 48, diagrammatically

cially shown in Figs. 20 to 24, inclusive, together limit the throw of the friction boxes 44, it is preferred to reduce the pressure exerted by the friction box on the carrier rods, after the rods are against the end stops, by distributing the total pressure over additional surfaces such as the stops 122, 123 for the box per se. Stops 122 and 123, Figs. 16 and 17, are shown as mounted on rods or bars 125, 126 respectively which are connected to move with the nuts 50 and the end stops 48 carried on the nuts. The tongue 118 therefore is adapted to contact one of its stops 122 and 123 at the same instant that the yarn carrier rod 42 contacts a stop 48 whereby the pressure on the yarn carrier rod is reduced.

The ordinary full-fashioned knitting machine as now manufactured also includes shock absorbing means and it is preferred to combine such shock absorbing means with the driving head forming part of the friction box accelerating means disclosed herein. In the arrangement shown for this purpose, the means for throwing out the clutch to release the driving member 86 from bar 84 is also employed. For absorbing shock and for releasing the clutch, blocks 128, 129 (Figs. 3, 4, 7, 18 and 19) are employed which are slidably mounted on a fixed horizontal rod or bar 132 adjacent the bar 84 for driving member 86. Blocks 128 and 129 are arranged at opposite ends of the path of movement of member 86 as viewed from the front of the machine. The positions of blocks 128 and 129 are controlled by the rods 125 and 126, respectively, which in turn are carried by the end stop nuts 50 as previously explained, the blocks being connected to the rods as hereinafter set forth. The shock absorbing action of the blocks 128 and 129 on the driving member 86 is governed by a cam 134 which is reciprocated at approximately half the speed of bar 84 and friction rod 55 by an oscillating lever 136 (Fig. 1) which is driven in turn by a link 138 (Fig. 2) pivoted to lever 136 at point 139 and to lever 70 at point 140. Lever 136 is connected to cam 134 by a means comprising a link 142 (Figs. 2, 4 and 6) pivoted to the upper end of the lever, the other end of link 142 being pivoted at 143 to a head 145 slidably mounted on a fixed rod or bar 146 and connected to cam 134 by a pair of rigid arms 148, best shown in Figs. 4 and 6, the end of arms 148 being shown bolted to the cam.

The cam 134 has a low portion 150 and high end portions 151 connected to low portion 150 by inclined portions 152 and it controls blocks 128 and 129 by means of lever systems 154 which are similar except that one is reversed with respect to the other. Each of said lever systems is connected to a block 128 or 129 by means of a link such as 156, best shown in Fig. 4. Each link 156 is pivoted to a lever arm 157 fixed to one end of a shaft 158 (Fig. 4) and which is journalled in a right hand head or block 160 or a left hand head or block 161 (Fig. 4) slidably mounted on a fixed bar 162. The other end of each shaft 158 has fixed thereto a second lever arm 163 at the free end of which is journalled a roller type cam follower 165. As shown in Figs. 4 and 20 to 24, when a cam follower 165 is on a high portion 151 of cam 134, the block 128 or 129 is moved toward the driving head 86. This is the condition as to block 128 shown in Fig. 4. As the cam 134 moves toward the right in this figure, the high portions 151 of the cam being level and of some length, the block 128 remains stationary for a time while the head 86 approaches it.

As cam 134 continues to move toward the right,

the follower 165 begins to move down the inclined portion 152 connecting the high and low portions 151 and 150, respectively and thereby moves the block 128 in the same direction as the driving member 86 but at a slightly slower speed than the driving member. Shortly after the block 128 starts moving a part of the driving member 86 overtakes and engages a part on the block, as shown in Fig. 18. As is clear from Figs. 10 and 11 the above referred to part on the driving member 86 is the tappet 96 which projects from the end of member 86 and which is adapted to engage an adjustable contact screw 167 in a turret like portion 168 of the block 128. As the tappet 96 continues to move at a faster speed than the block 128 the end of tappet 96 forces the right roller 94 leftward out of its wedging and clutching position to release the head 86 from the bar 84. Immediately upon release of the right roller 94 the driving head 86 is carried along by the rod 98 which is driven at this time by an auxiliary friction box 172 on the friction box rod 55. The auxiliary box 172 is connected to the rod 98 by one of the collars 116 and a collar 173 on the rod, as shown in Figs. 17 and 20 to 24, which are placed on each side of and in juxtaposed relation to a tongue 175 on the auxiliary friction box so as to prevent lost motion between the box and the rod 98. The driving head 86 continues to move at a faster speed than the block 128 through the auxiliary friction box 172 until the head engages stop screw 170 also adjustably carried in turret portion 168 of the block 128 (Fig. 19) after which the head 86 is carried along by the box 172, as hereinafter set forth, at the speed of the block. As the speed of the block 128 is reduced, the speed of the rod 98 and the auxiliary friction box 172 is also reduced and the friction box 44 which is still moving with and at the same speed as the friction rod 55, immediately overtakes and engages the right collar 116. Engagement of the box 44 with the collar 116 reduces the speed of the box 44 to that of the rod 98.

Further, as follower 165 on head 160 moves down the inclined portion 152 of cam member 134, shaft 158 and lever arms 157 and 163 turn gradually in the counterclockwise direction, thereby reducing the speed of block 128, the head 86, the rod 98, friction boxes 44 and 172 and the carrier rod 42. This reduction in speed continues and as the follower approaches the low portion of the cam, the system including said head 86, friction box 44 and carrier rod 42 is moving very slowly as the tongue 118 of the box 44 contacts and is stopped by the stop 123 and the carrier rod engages its end stop 48. The relationship is the same between head 86, screws 167 and 170 in a turret like portion 169 of the block 129 and stop 122 when the member approaches block 129.

Throughout the accelerating portion of the stroke of head 86 from left to right, illustrated in Figs. 20 to 24 inclusive, the stress in rod 98 is one of compression due to pressure of tongue 118 against the left block 116 as illustrated in Fig. 21. After the friction box 44 and carrier rod 42 reach full speed, there is little stress if any in rod 98 because the friction box and the driving head 86 move at the same speed until head 86 contacts bolt 170 and block 128 at which time the stress in rod 98 changes to one of tension due to the pressure of the tongue 118 against the right or leading block 116, as illustrated in Fig. 22. At the moment tongue 118 engages stop 123, however, the cam 134 still permits right hand cam follower 165, controlling block 128 to settle

slightly toward the low portion 150 of the cam. This final movement of the follower 165 is caused by the auxiliary friction box 172, on the high speed friction box rod 55, which continues to apply pressure to the rod 98 as long as the rod 55 continues to move in the same direction. As shown in Figs. 20 and 24, when the left or right follower 165 is in engagement with the low portion 150 of the cam 134 which corresponds to the limit of movement of the rod 98 in the left and right directions, respectively, there is a slight clearance between the collars 116 at both sides of the tongue 118. This slight clearance between the collars 116 and tongue 118 permits the auxiliary friction box 172 to maintain pressure against rod 98 and thereby hold the rod at the limit of its movement in either direction until the direction of its movement is reversed by the cam 62 and the associated parts, as hereinafter set forth.

In order to bias cam follower 165 toward the cam 134, the lever arms 157 have extensions 177 which have noses 178 formed thereon. The noses 178 are normally in contact with the closed ends of spring pressed hollow plungers 180 (Fig. 15) mounted in portions 182 of blocks 160. A compression spring 184 abuts the closed end of each plunger 180 and one end of a bolt 186 which is adjustably mounted in the closed end of member 182 so as to vary the pressure of the spring against the closed end of member 180 and the extension 177 of the lever 157. Further, the extension 177 of each lever 157 has a lateral extension 188 (Figs. 7 and 13) in which is a stop bolt 190 adapted to engage a portion of the heads 160 and 161 to limit the counterclockwise or clockwise movement of the right and left levers 163 respectively, if for some reason the levers 163 become misadjusted relative to the shafts 158.

It will be noted that for purposes of illustration the diagrammatic Figs. 20 to 24 show the lever systems 154 as connected directly to rods 125 and 126. However, the lever systems 154 and heads 160 and 161 on which they are directly mounted are actually supported for sliding movement by the fixed bar 162 shown in Figs. 5-7 but which is not shown in Figs. 20-24 and the bars 125 and 126 for moving systems 154 as well as the stops 122 and 123 from the fashioning nuts 50 are shown in their actual relative proportions in Figs. 4-7, inclusive, 16 and 17. As shown in Figs. 4 and 5, rod 125 is connected to the left hand head 161 by means of a bracket 192 the rod also being connected to stop 122 for the friction box 44, as hereinbefore set out.

Bracket 192 is shown in Fig. 5 as having a portion in sliding engagement with the rod 126 for supporting the end of rod 125 (Fig. 16). As shown in Fig. 17, rod 125 is connected to move the stop 122 also but, as shown in Figs. 5 and 16, rod 125 is interrupted between left hand block 161 and stop 122 to avoid a structural feature of the machine and, in order to transmit operating forces from the left hand nut 50 to the stop 122, a jumper rod 194 is employed. Rod 194 is connected at its left end to rod 125 by a bracket 195 shown in Figs. 1, 3 and 16. Bracket 195 also has a portion providing a sliding support on the rod 126. Rod 194 connects at its right end to the portion of rod 125 beyond the interruption through a bracket 198 which also has a portion for sliding engagement with the rod 126, the bracket 198 also having the stop 122 for box 44 formed thereon. Rod 126 has a bracket 200 secured thereto (Figs. 4, 7 and 16) by means of

which the rod is connected to the right hand block 160, the bracket 200 being of the same general type as bracket 192. Rod 126 has a bracket 201 secured thereto which also has a portion slidably engaged with the rod 125, the bracket 201 also having the stop 123 formed thereon. Rod 126 connects with the nut 50 for the end stops at the right hand end of the machine as shown in the diagrammatic views, Figs. 20-24.

In addition to the rods previously mentioned, there is shown in Figs. 4, 5, 6 and 7 a fixed rod 202 used as a guide to prevent heads 145, 128 and 129 from turning on their supporting rods, head 145 having fork portions 204 (Figs. 4 and 6) for this purpose embracing rod 202 and heads 128 and 129 having forks 205 and 206, respectively, embracing rod 202 for the same purpose.

The manner of operation of the mechanism herein disclosed will be obvious to those skilled in the art from the foregoing description but the operation of the mechanism will be summarized for purposes of convenience, as follows:

The member 86 for assisting the friction box 44 in driving the carrier rod for laying the body or other yarn is automatically engaged by clutch 88 to the reciprocating driving bar 84 at the start of each stroke of the bar to transmit accelerating forces to the box 44. The driving bar has a longer throw or stroke than the stroke of the box 44 and the box therefore must be unclutched automatically from the driving bar as the box approaches the end of a stroke and is brought nearly to rest before contacting a limit stop 122 or 123, the driving bar continuing to the end of its path and then beginning its return stroke. On the return stroke of the driving bar 84, it is again clutched automatically to the member 86 to initiate a return stroke or movement of the member and the friction box without material or substantial slippage between the member and the driving bar.

As shown in Fig. 20 the friction box 44 and driving head 86 are at the left end of their movement from right to left which also corresponds to the starting position of the parts from left to right. In this position both right and left collars 116 are spaced from the tongue 118, the spaces being indicated at 120. As the cam 62 reverses the movement of the friction box rod 55, in the direction from left to right as viewed in Fig. 2 and 20 to 24, the bar 84 and cam 134, are also moved toward the right, the bar 84 moving at the same speed as the friction box rod 55. Immediately upon movement of the bar 84, the right hand roller 94 (Fig. 10) is wedged between the bar and the inclined surface of the recess 92 and the driving head 86 is carried along with and at the same speed as the bar. Movement of driving head 86 toward the right causes the tongue 102 of the member 104 to bear against the right collar 100 (Fig. 10) to drive the rod 98 with the head. Movement of the rod 98 engages the left collar 116 with the tongue 118 of the friction box 44 to thereby carry the friction box and carrier rod 42 along with the rod 98 as shown in Fig. 21. Also as shown in Fig. 21, the cam 134 is moving in the same direction but, as hereinbefore set forth, at a slower speed than the friction box rod 55, the right hand high portion 151 of the cam maintaining the right hand lever system 154 and the block 128 stationary as the driving head 86 approaches the block 128.

Upon continued movement of the friction box rod 55, the driving head 86 and rod 98, and the cam 134 toward the right, the follower 165 of the

11

right hand lever system 154 starts down the right inclined surface 152 of cam 134 which starts to move the block 128 toward the right but at a slightly slower speed than the speed at which the driving head is travelling. Continued movement of the head 36 at full speed causes the tappet 98 to overtake and engage the screw 167 in the slower moving block 128. As the head continues to move the tappet forces the right roller 94 out of its wedging position to disengage the driving connection between the head and the bar 84. As the parts continue to move toward the right the auxiliary friction box 172, which is moving at full speed with the friction box rod 55, pulls the driving member 86 against the stop screw 176 through the connection of the box 172 with the rod 98. The driving member 86, rod 98 and friction box 172 thereupon travel at a slower speed as controlled by the cam 134. The friction box 44, which is still travelling at the same speed as rod 55, thereupon overtakes the right hand collar 116, as shown in Fig. 22, and is slowed to the same speed as the rod 98. The parts continue to move toward the right but at a gradually diminishing speed under the control of the right inclined surface 152 of the cam 134 so that the tongue 118 of the friction box 44 engages the stop 123 and the carrier rod 42 engages its stop 48, as shown in Fig. 23, with very little impact.

It will be seen in Fig. 23 that at the time of engagement of the tongue 118 with the stop 123 and the carrier rod 42 with the stop 48, the right hand follower 165 has not engaged the low portion 150 of the cam 134. At this time the auxiliary friction box 172 continues to exert pressure on the rod 98, toward the right to thereby move the right follower 165 against the low portion 150. This final movement of the follower 165 causes both right and left collars 116 to be spaced from the tongue 118, as indicated at 128 in Fig. 24. The friction box rod 55 continues toward the right to complete its movement, the movement of the rod 55 then being reversed by the cam 62 and the cycle of movements illustrated in Figs. 20 to 24, inclusive, is repeated while the parts are moving from right to left.

From the foregoing it will be understood that the driving head 36 acts as a positive means to assist the friction box 44 in overcoming the inertia of the carrier rod as it is accelerated at the start of its movement and thereby maintain a predetermined relation between the box and the means for reducing the speed of the box and carrier rod near the end of their movement. Further, that a much lighter frictional engagement may be maintained between the friction boxes 44 and 172 and the friction rod 55, to complete the stroke of the carrier rod, which will greatly reduce the wear and the heat generated as the rod 55 continues to slide through the boxes after the boxes have been stopped as hereinbefore set forth.

Of course, the improvements specifically shown and described by which the above results are obtained, can be changed and modified in various ways without departure from the invention herein disclosed and hereinafter claimed.

We claim:

1. In a full-fashioned knitting machine, the combination with a friction box rod, yarn carrier rods and a friction box thereon on said friction box rod, of means for reciprocating said friction box comprising in addition to said friction box rod, a head mounted for reciprocation parallel to the friction box rod, a connection be-

12

tween said head and the friction box for transmitting a driving force from the head to the box, means for intermittently driving said head and means for disconnecting said head from its driving means and retarding the head as the friction box approaches the end of its stroke.

2. In a full-fashioned knitting machine, the combination as set forth in claim 1 and in which the means for driving the head includes a member which reciprocates constantly through a distance greater than the stroke of the yarn carrier rods and a disconnectible clutch between said member and the head.

3. In a full-fashioned knitting machine, the combination as set forth in claim 1 and in which the means for driving the head includes a member which reciprocates constantly through a distance greater than the stroke of the yarn carrier rods, and a disconnectible clutch between said member and the head which reconnects the head to the member of the driving means automatically upon reversal of its direction of movement by the interaction of the reciprocating member and a portion of the clutch.

4. In a full-fashioned knitting machine the combination as set forth in claim 1 and in which the means for driving the head includes a member which reciprocates constantly through a distance greater than the stroke of the yarn carrier rods, and a disconnectible clutch between said member and the head, and the means for disconnecting the head from the reciprocating member includes a pair of contact blocks having alternately part time contact with said clutch means to release the head from said member and having contact with the head, and a cam means to control the movement of the blocks to thereby control the motion of the head and the box after the clutch means has released the head.

5. In a full-fashioned knitting machine, the combination as set forth in claim 1 and in which the means for driving the head includes a member which reciprocates constantly through a distance greater than the stroke of the yarn carrier rods, and a disconnectible clutch between said member and the head, and the means for disconnecting the head from the reciprocating member includes a pair of contact blocks having alternately part time contact with said clutch means to release the head from said member and having also contact with the head, a cam means to control the movement of the blocks to thereby control the motion of the head and the box after the clutch means has released the head, the cam means includes a reciprocating cam having two high sections connected by a low section and moving at a lesser rate of speed than the driving means, cam followers cooperating with said cam, lever systems on which said followers are journaled and which are connected to the contact blocks to determine the movement of the blocks together with nuts for end stops, second blocks on which said lever systems are pivoted and bars movable with said nuts for moving said second blocks.

6. The combination with the friction box rod and the friction box of a full-fashioned knitting machine of a friction box accelerator member reciprocating synchronously with the friction box rod, a head in contact with said member, means to clutch said head firmly to the member as the member and friction box rod initiate a movement in one direction and release it therefrom as the rod approaches a point at which its

13

movement reverses, and a connection from said head to the friction box.

7. The combination as set forth in claim 6 and in which a roller clutch means acts automatically to connect the head to the accelerator member as the member reverses its direction.

8. The combination as set forth in claim 6 and in which a roller clutch means acts automatically to connect the head to the accelerator member as the member reverses its direction together with a cam actuated member for releasing the clutch as the friction box approaches the end of a stroke.

9. The combination as set forth in claim 6 and in which a roller clutch means acts automatically to connect the head to the accelerator member as the member reverses its direction, a cam actuated member releases the clutch as the friction box approaches the end of the stroke, and the means for releasing the clutch also acts to slow the head and thereby acts as a shock absorber by slowing the friction box through the connection between the head and the box.

10. The combination as set forth in claim 6 and in which a roller clutch means acts automatically to connect the head to the accelerator member as the member reverses its direction, a cam actuated member releases the clutch as the friction box approaches the end of a stroke, the means for releasing the clutch also acts to slow the head and thereby acts as a shock absorber by slowing the friction box through the connection between the head and the box, the cam for the cam actuated means reciprocates but at a lower speed than the friction box and the cam actuated means includes a cam follower pivoted on an axis fixed at times the follower is active to actuate the releasing means.

11. The combination as set forth in claim 6 and in which a roller clutch means acts automatically to connect the head to the accelerator member as the member reverses its direction, a cam actuated member releases the clutch as the friction box approaches the end of a stroke, the means which releases the clutch also acts to slow the head and thereby acts as a shock absorber by slowing the friction box through the connection between the head and the box, the cam for the cam actuated means reciprocates but at a lower speed than the friction box, the cam actuated means includes a cam follower pivoted on an axis fixed at times the follower is active to actuate the releasing means, a nut for moving end stops for fashioning and a connection between the nut and the axis of the cam follower to move the axis with the nut.

12. The combination as set forth in claim 6 and in which a roller clutch means acts automatically to connect the head to the accelerator member as the member reverses its direction, a cam actuated member releases the clutch as the friction box approaches the end of a stroke, the means which releases the clutch also acts to slow the head and thereby acts as a shock absorber by slowing the friction box through the connection between the head and the box, the cam for the cam actuated means reciprocates but at a lower speed than the friction box and the cam actuated means includes a cam follower pivoted on an axis fixed at times the follower is active to actuate the releasing means, a nut for moving end stops for fashioning and a connection between the nut and the axis of the cam follower to move the axis with the nut, the nut has end stops for carrier rods thereon, the connection between the nut and the axis of the

14

cam follower has a stop thereon and the friction box has a tongue fixed thereon arranged to contact said stop on the connection at approximately the time the carrier rod contacts an end stop on the nut.

13. The combination as set forth in claim 6 and in which a roller clutch means acts automatically to connect the head to the accelerator member as the member reverses its direction, a
10 cam actuated member releases the clutch as the friction box approaches the end of a stroke, the means which releases the clutch also acts to slow the head and thereby acts as a shock absorber by slowing the friction box through the
15 connection between the head and the box, the cam for the cam actuated means reciprocates but at a lower speed than the friction box and the cam actuated means includes a cam follower pivoted on an axis fixed at times the follower
20 is active to actuate the releasing means, a nut for moving end stops for fashioning, a connection between the nut and the axis of the cam follower to move the axis with the nut; the nut has end stops for carrier rods thereon, the connection between the nut and the axis of the cam
25 follower has a stop thereon, the friction box has a tongue fixed thereon arranged to contact said stop on the connection at approximately the time the carrier rod contacts an end stop on a nut,
30 and the connection between the head and friction box provides a lost motion permitting the connection a relatively small movement after the friction box has come to a stop.

the friction box has come to a stop.

14. The combination as set forth in claim 6
35 and in which a roller clutch means acts automatically to connect the head to the accelerator member as the member reverses its direction, a cam actuated member releases the clutch as the friction box approaches the end of a stroke, the
40 means for releasing the clutch also acts to slow the head and thereby acts as a shock absorber by slowing the friction box through the connection between the head and the box, the cam for the cam actuated means reciprocates but at a lower
45 speed than the friction box and the cam actuated means includes a cam follower pivoted on an axis fixed at times the follower is active to actuate the releasing means, a nut for moving end stops for fashioning, a connection between the nut and the axis of the cam follower to move the axis with the nut, the nut has end stops for carrier rods thereon, the connection between the nut and the axis of the cam follower has a stop thereon, the friction box has a tongue
50 fixed thereon arranged to contact said stop on the connection at approximately the time the carrier rod contacts an end stop on the nut, the connection between the head and friction box provides a lost motion permitting the connection
55 a relatively small movement after the friction box has come to a stop, and the connection between the head and the friction box comprises two stop blocks on opposite sides of the tongue and spaced apart a distance slightly greater than
60 the width of the tongue in the direction of motion of the friction box.

15. The combination as set forth in claim 1 in which the means for driving the head includes a member which reciprocates constantly through a distance greater than the stroke of the yarn carrier rods, and a disconnectible clutch between said member and the head which is of the roller type and which reconnects the head to the member of the driving means automatically upon reversal of its direction of movement.

by interaction between the reciprocating member and a portion of the clutch.

16. In a full-fashioned knitting machine, the combination with a driven member of a reciprocating accelerator member, a head in contact with said member, automatic clutch means acting to clutch said head and member firmly together as the accelerator member initiates a movement in one direction, a cam controlled means for acting on said clutch means to release the head from the accelerator member and to slow the head relatively to the member as the head approaches an end of a stroke in said direction, and a connection to transmit an accelerating pressure from said head to the driven member as the head accelerates and a retarding pressure from the head to the driven member as the head slows down.

17. In a full-fashioned knitting machine, the combination as set forth in claim 16 and in which the cam controlled means includes a cam reciprocating parallel to the accelerator member but at a slower rate of speed and having high parts near its ends and a low part connecting said high parts, cam followers each passing from one of said high parts to said low part or the reverse as the head approaches an end of its path, and pivoted levers on which said followers are journaled and which have operating connections with said clutch arranged to act one at a time to disconnect the clutch as the follower moves from a high to the low part of the cam, said last named connections retarding the movement of the head after disconnecting the clutch.

18. In a full-fashioned knitting machine, the combination as set forth in claim 16 and in which the cam controlled means includes a cam reciprocating parallel to the accelerator member but at a slower rate of speed and having high parts near its ends and a low part connecting said high parts, cam followers each passing from one of said high parts to said low part as the head approaches an end of its path, pivoted levers on which said followers are journaled and which have operating connections with said clutch arranged to act one at a time to disconnect the clutch as the follower moves from a high to the low part of the cam, said last named connections retarding the head after disconnecting the clutch, together with nuts mounted to move in each narrowing cycle and to be held stationary during knitting cycles, end stops on said nuts, a bar connected to move with said nuts and supporting blocks connected to said bars on which the levers are pivoted.

19. In a full-fashioned knitting machine, the combination with a yarn carrier rod of a reciprocating accelerator member, a head in contact with said member, a box member mounted to reciprocate parallel to and synchronously with said accelerator member and having a connector adapted to be engaged with said yarn carrier rod to drive it when desired, stops for said yarn carrier rod and said box member, an automatic clutch means acting to clutch said head and accelerator member firmly together as the member and friction box initiate a movement in one direction, means acting on said clutch means to release it and including a tappet piece on the head and a block member with which the tappet piece contacts to move the tappet piece relative to the head and into position to release the clutch means, a connection between said head and said box member to transmit accelerating and retarding pressures from the head

to the box member and carrier rod but providing a limited lost motion between the connection and box member, and a box member connected to said connection without lost motion therebetween and operated frictionally to reciprocate at the same number of strokes per minute as the head and acting through the connection to maintain the head in constant position relatively to said block member from the time the clutch is released to cause said tappet piece to maintain the head unclutched until the accelerator member reverses its direction of movement.

20. In a full-fashioned knitting machine, the combination with the friction box rod, the yarn carriers and box therefor on said friction box rod, of means for reciprocating said box comprising, in addition to said rod, a head mounted for reciprocation parallel to the rod, a connection between said head and the box for transmitting a driving force from the head of the box, means for intermittently driving said head, means for disconnecting said head from its driving means and retarding the head as the box approaches the end of its stroke, said intermittent driving means including a member reciprocating synchronously with the friction rod, a roller type clutch acting automatically to connect the head to said reciprocating member as the member reverses its direction, said connection including a second rod and means providing a small amount of lost motion between the second rod and said friction box, and a second friction box connected to said second rod to prevent lost motion therebetween.

21. In a full-fashioned knitting machine having a reciprocating driving member, a head to be reciprocated, and a clutch on the head to transmit driving thrust from the driving member to the head, a combined means for releasing the head from said member and slowing down the head comprising a slidably mounted block, a pivoted lever system connected to said block at one end and having a cam follower journaled thereon at the other end and a reciprocating cam cooperating with said follower having a straight high portion at one end and a straight low portion connected to said high portion by an inclined portion, said cam and lever system holding said block in the path of the head and controlling the block to contact and release said clutch on the head and to thereafter slow the head to a standstill while the follower is moving down said inclined portion of the cam.

22. In a full-fashioned knitting machine having a friction rod, a friction box on said rod, a yarn carrier rod connected to said box and end stops for said box and carrier rod, means for accelerating the box and carrier rod to the speed of said friction rod comprising a driving head movable through a greater distance than said box and carrier rod, means connecting the head to said box to transmit a driving force from the head to the box, means for intermittently driving said head, means for disconnecting said head from its driving means, means for retarding said head and disconnecting means, and a second friction box on said friction rod for maintaining said head in contact with said disconnecting means during the retarding action to thereby retard said first box and carrier rod as said box and carrier rod approach said end stops, said second box continuing to move said head through said greater distance after said first box and carrier rod engage said stops.

23. In a full-fashioned knitting machine hav-

17

ing a friction rod, a friction box on said rod, a yarn carrier rod connected to said box and end stops for said box and carrier rod, means for accelerating the box and carrier rod to the speed of said friction rod comprising a driving head, means connecting said head to said box to transmit a driving force from the head to the box, means for intermittently driving said head, means for disconnecting said head from its driving means, means for retarding said head and disconnecting means, and a second friction box on said friction rod for maintaining said head in contact with said disconnecting means during the retarding action to thereby retard said first box and carrier rod as said box and carrier rod approach said end stops.

GOTTLOB BITZER.
